CLAIM

The ornamental design for a cassette for storing flat articles, particularly data carriers, as shown and described.

DESCRIPTION

FIG. 1 is a left side elevational view of a cassette for storing flat articles, particularly data carriers, showing our new design;

FIG. 2 is a front view thereof;

FIG. 3 is a right side view thereof;

FIG. 4 is a rear view thereof;

FIG. 5 is a top view thereof;

FIG. 6 is a bottom view thereof; and,

FIG. 7 is a perspective view thereof showing the design in the open position.
